UNITED STATES PATENT OFFICE.

BUDD D. BOHANAN, OF BOSTON, MASSACHUSETTS, ASSIGNOR TO THOMAS G. PLANT COMPANY, OF BOSTON, MASSACHUSETTS, A CORPORATION OF MASSACHUSETTS.

LAST JACK.

Application filed December 9, 1922. Serial No. 605,887.

To all whom it may concern:

Be it known that I, BUDD D. BOHANAN, a citizen of the United States, residing at Boston, in the county of Suffolk and State of Massachusetts, have invented new and useful Improvements in Last Jacks, of which the following is a specification.

The present invention relates to jacks for supporting lasts on certain machines employed in the operations of shoe making, and it consists, essentially, in the provision of means for supporting the middle part of the last and preventing its breaking down between the heel and toe supports under the heavy pressures applied in some of these operations. In particular, the operation of leveling the sole of the shoe, when performed in the automatic machines devised for that purpose, is one which applies severe bending stress to the last which supports the shoe. In such machines the jack by which the last is supported comprises two separated uprights, one of which carries a last pin adapted to enter the usual socket or thimble in the heel part of the last and the other of which has a rest to support the toe end of the last. Between these members the last is unsupported and, under the heavy pressure in leveling the sole, is liable to fail. This liability is particularly great with hinged lasts, and one large cause of trouble and expense in shoe factories has been the failure of hinged lasts in leveling machines.

The same tendencies exist, although perhaps in a less degree, in other machines employed in the shoe making art for operating on shoes while on their lasts.

Having reference to the foregoing, my invention consists in the provision of a last-holding jack having, in addition to heel and toe supports, an intermediate or instep support arranged and operating to hold up the middle part of the last and prevent breakage under heavy pressure applied against this part of the last.

In the drawings:—

Figure 1 is a perspective view showing one form of my improved jack with a last in place upon it.

Figure 2 is a sectional view of the inter-

mediate support or instep support on a larger scale, the saddle part of such support being represented without its preferred covering or sheath of leather.

Figure 3 is an elevation of the upper part of the intermediate support, as seen from the right of Figure 2.

Like reference characters designate the same parts wherever they occur in all the figures.

In the drawings herewith presented, which represent the embodiment of my invention in a jack for a type of automatic leveling machine already on the market, the letter *a* represents a rigid upright which is adapted to support the toe of the last and has a rest *b* recessed in its upper side to receive the toe part of the last. This upright may be considered as the toe support of the jack. *c* is an arm or upright which extends in a substantially vertical direction from a pivotal mounting on a lower part of the machine (not shown here). The arm *c* carries a last pin *d* adapted to enter the thimble or socket with which lasts are commonly provided. The pivotal mounting or arm *d* allows it to accommodate lasts of different lengths, the toe part of each of which is placed on the rest *b* of the fixed upright, as is well understood in this art.

The last itself is shown at *e*. This showing is diagrammatic in order to indicate the purpose and utility of the invention, rather than illustrative of any actual condition because, when, in actual operation, the last is placed on the jack, it is within a partially completed shoe and, therefore, enclosed and embraced by the parts of the shoe. Also the large majority of the lasts which would be mounted on such a jack are hinged between the heel and fore part and although the representation of the last here does not show the hinged construction, I desire it to be understood that such representation is intended to typify and include any form of last, whether hinged or not.

The arm *f* represents a lever which is an adjunct of the machine and serves to pull down on a strap which is passed over the lasted shoe when applied to the jack so as

to hold it in place during the leveling operation. But as these elements are parts of the machine which neither affect the new step of the present invention nor are affected thereby, there is no necessity for further description or illustration of them in this specification.

An intermediate or instep support is provided by a post *g* and a saddle *h*. The post 10 is supported at its lower end in a socket piece *j* which is secured to the side of the upright *a*, and the saddle is connected in an adjustable manner to the post by a screw *k* contained telescopically in the post and 15 engaged with a nut *l* which rests on the top of the post. Rotation of the screw when the nut is turned is prevented by a pin *m* which projects from the screw through a slot in the side of the post, as 20 shown in Figure 2, while separation of the nut from the post is prevented by a clip *n* screwed to the side of the post and having a flange *n'* which enters a groove *o* in the nut and overlaps a flange *p*. By turning 25 the nut the saddle may be adjusted to lasts which, by reason of different lengths or styles, project more or less from the line between the toe and heel supports, and thus the intermediate support may be set to take 30 initially as much as may be desired of the pressure applied to the last.

Preferably the saddle is pivoted to the screw *k* on a pivot *q* in order to accommodate itself to the slope of the instep; and 35 preferably, also, it has a long flange *r* extending toward the last bottom and so placed as to resist overturning of those styles of last which spring or are offset in their middle parts far to one side of a straight 40 line between their toe and heel extremities.

In construction the saddle is preferably made of cast iron, or brass, or other material having sufficient rigidity and is covered with a sheathing *s* of leather or other material which is soft enough to avoid 45 injuring the shoe upper on the last. The covering *s* shown in Figure 3 is made of leather cut and shaped to lie in and fit the concave upper side of the saddle body and to be lapped around the flanges *r* and *r'*, and the end *r''*, being secured by screws *t*, *t'* and *t''*.

The slotted plate *u* attached to the upright *a* and shown at Figure 1, through 50 which the post *g* passes, is a stop to prevent the saddle being crowded toward the toe rest *b*, by the wedging effect of the last instep, too far to give the desired support. It will be noted that the socket *j* in which 55 the lower end of the post is set, is at a relatively low level below the toe-engaging rest of the rigid upright *a*, and that the arrangement of the socket, the post and the saddle is such as to bring the line of supporting reaction of the instep support 60

nearly perpendicular to the length of the last, and consequently nearly into coincidence with the direction in which pressure is exerted upon the last by the leveling tool when in operation upon the bottom of a 70 lasted shoe. Hence the tendency of the instep support to be displaced by the operating pressure of the machine, and the component of force then borne by the stop plate *u*, is relatively small. The forward 75 end of the slot in the stop plate *u* is also a stop to prevent the saddle from falling too far out of place when the last is removed.

Last supporting jacks having the same 80 principles may be made in other forms and modes of construction for use with other machines.

What I claim and desire to secure by Letters Patent is:

1. In combination with a last-supporting jack comprising a rigid upright adapted to support one end of the last, and a second upright adapted to support the other end of the last, an intermediate instep support 90 consisting of a post mounted at its lower end on said rigid upright at a relatively low point and a saddle mounted on the upper end of said post.

2. In combination with a last-holding jack having separated toe and heel supports, an intermediate support comprising a post mounted at its lower end on the toe support and a saddle on the upper end of such post adapted to engage the instep of the last, the line between the saddle and lower end of the post being nearly perpendicular to the line between the last-engaging parts of said toe and heel supports.

3. A last-holding jack comprising in combination a rigid toe support, a wholly separated heel support, an intermediate instep support mounted at a low point on the toe support, and a stop fixed to the toe support in position to engage the intermediate support between the upper and lower ends of the latter.

4. A last-holding jack comprising separated toe and heel supports and an intermediate support comprising a post, a saddle held by said post and formed to receive the instep part of a last and having a flange disposed at one side of such last to resist overturning thereof.

5. A last-supporting jack comprising a heel support, a toe support, and an intermediate support, said intermediate support consisting of a post mounted at its lower end on the toe support, a screw telescopically contained in said post, a nut mounted on the post and engaged with said screw, and a saddle pivoted to the upper end of said screw, said saddle being adjustable independently of the toe support.

6. In a last supporting jack having a

rigid toe support and a separate heel support, a socket piece fixed to the toe support, a slotted stop plate fixed to the toe support above said socket piece, a post mounted at its lower end in said socket piece and rising through the slot of such stop plate, and a saddle mounted on the upper

end of said post adapted to engage an intermediate part of the last which is mounted on said toe and heel supports. ¹⁰

In testimony whereof I have affixed my signature.

BUDD D. BOHANAN.
